UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
ENGLAND.

SIGHTING APPARATUS FOR ORDNANCE.

1,306,413.

Specification of Letters Patent. Patented June 10, 1919.

Original application filed June 22, 1915, Serial No. 35,729. Divided and this application filed November 27, 1915. Serial No. 63,890.

To all whom it may concern:

Be it known that we, Sir ARTHUR T. DAWSON, knight, and GEORGE T. BUCKHAM, both subjects of the King of Great Britain, residing at and whose post-office addresses are 5 Vickers House, Broadway, Westminster, in the county of London, England, have invented certain new and useful Improvements in or Relating to Sighting Apparatus for Ordnance; and we hereby declare the following to be a full, clear, and exact description of the invention, such as will enable others skilled in the art to which it appertains to make and use the same.

15 In connection with ordnance sighting apparatus, it is usual to provide means whereby, when the trunnions of a gun are inclined to the horizontal as a result of the gun carriage resting on uneven ground, the sight 20 will be deflected to compensate for the lateral error which would otherwise occur. In addition to this error there is however a further error which as is well understood affects the laying of the gun for range, this 25 error resulting from the fact that the angle between the axis of the gun and the sight line—*i. e.* the angle of tangent elevation—when projected on to a vertical plane is less when the trunnion axis is inclined than 30 when it is level, and therefore less than the angle corresponding to the range registered on the range dial or its equivalent, and the chief object of the present invention is to devise improved means for correcting this 35 error.

According to this invention we provide means for automatically correcting the angle of tangent elevation by varying the reading of the range indicating device, the amount 40 of such correction being dependent upon the inclination of the gun trunnions and the range of the object.

For this purpose we may provide means whereby the adjustment of a spirit level or 45 other gravity controlled device to its zero position moves a cam into such a position that when the gun is being elevated for range the cam effects relative movement between the range dial and its pointer.

50 In order that the said invention may be clearly understood and readily carried into effect we will describe the same more fully

with reference to the accompanying drawings, in which:

Figures 1, 2 and 3 are respectively a side 55 elevation, a plan and a sectional rear elevation showing in a more or less diagrammatic manner a constructional form of the invention for effecting relative movement between the range dial and its pointer, and 60

Fig. 4 is a section taken approximately on the line 1, 1 of Fig. 1.

A is one of the gun trunnions and B represents the aforesaid cam.

E represents the aforesaid spirit level by 65 the adjustment of which the cam B is moved into such a position that during the elevation of the gun for range the said cam will effect relative movement between the range dial F and its pointer F'. This level, in the 70 example shown, is constituted by a liquid and bubble containing tube mounted in a casing which is pivotally mounted on a bracket G carried by the sight arm which moves during pointing only. The bubble is 75 adapted to be brought to its zero position by means of a handwheel E' actuating a worm e' (Fig. 2) which gears with a worm wheel sector e on the casing of the bubble containing tube. This worm also gears with a worm 80 wheel sector formed on one arm of a rocking lever E² so as to impart thereto an angular movement proportional to the inclination of the trunnions. The rocking lever carries a 85 roller e² engaging in a slot b² on the rear surface of a link B' having a slot B (constituting the aforesaid cam) which when the link is in its normal position is concentric 90 with the trunnion axis. This link is pivoted at b to the bracket G. The slot B receives a 95 roller f' on the end of the range pointer F' which is rotatably mounted on the boss of the range dial F. The dial and pointer are carried on the cradle. In the normal position (*i. e.* for level ground) the roller f' moves in the slot B without affecting the position of the pointer F' during the elevation of the gun for range, since as above stated the slot B is, in this condition of affairs, concentric with the gun trunnions. When, however, the bubble E is brought to its zero position to correct for sloping ground the slotted link B' is rocked about its pivot b by the roller e² and the slot b² and the slot

- B no longer remain concentric with the trunnion axis so that as the gun is being elevated for range the slot B imparts movement to the pointer F' proportional to the angle of 5 inclination of the trunnions and to the range. By adjusting the range dial to maintain the desired graduation opposite the pointer the necessary correction is imparted to the angle of tangent elevation.
- 10 What we claim and desire to secure by Letters Patent of the United States is:—
1. In ordnance sighting apparatus, the combination with the range indicating device, of a slotted member, a projection connected to the range indicating device and engaging said slotted member, means for adjusting said slotted member in accordance with the degree of inclination of the gun trunnions, and means for effecting relative 15 movement between said slotted member, and projection in accordance with the range of the target.
  2. In ordnance sighting apparatus, the combination with the members of a range indicating device, of a slotted member, a projection connected to one member of the range indicating device and engaging said slotted member, means for adjusting said slotted member in accordance with the degree of inclination of the gun trunnions, and means for effective relative movement between said slotted member and projection in accordance with the range of the target. 25
  3. In ordnance sighting apparatus of the kind having an independent line of sight, the combination with the range indicating 30

device carried by the gun cradle, of a member moving only during the pointing of the gun, an arm pivoted to said member and formed with a slot which is normally concentric with the axis about which said member moves, a projection connected to the range indicating device and engaging in said slot so that relative movement occurs between the slot and the projection during the 40 ranging of the gun, and means for adjusting said slotted arm in accordance with the degree of inclination of the gun trunnions. 45

4. In ordnance sighting apparatus having an independent line of sight, the combination with the members of the range indicating device carried by the gun cradle, of a sight arm moving only during the pointing of the gun, a slotted member pivoted to said sight arm with its slot normally concentric 50 with the axis about which said sight arm moves, a projection connected to one member of the range indicating device and engaging said slotted member so that relative movement occurs between the slotted member and the projection during the ranging of the gun, and means for adjusting said slotted member in accordance with the degree 55 of inclination of the gun trunnions. 60

In testimony whereof we affix our signatures in the presence of two witnesses.

ARTHUR TREVOR DAWSON.
GEORGE THOMAS BUCKHAM.

Correction in Letters Patent No. 1,306,413.

It is hereby certified that in Letters Patent No. 1,306,413, granted June 10, 1919, upon the application of Arthur Trevor Dawson and George Thomas Buckingham, of Westminster, London, England, for an improvement in "Sighting Apparatus for Ordnance," an error appears in the printed specification requiring correction as follows: Page 2, line 31, claim 2, for the word "effective" read *effecting*; and that the said Letters Patent should be read with this correction that the same may conform to the record of the case in the Patent Office.

Signed and sealed this 1st day of July, A. D., 1919.

[SEAL.]

J. T. NEWTON,

Commissioner of Patents.
